UNITED STATES PATENT OFFICE.

WILLIAM L. BIERBRAUER, OF WEST HOBOKEN, NEW JERSEY, ASSIGNOR
TO EUGENE DIETZGEN COMPANY, OF CHICAGO, ILLINOIS, A CORPO-
RATION OF ILLINOIS.

PHOTOGRAPHIC-PRINTING APPARATUS.

No. 827,954.

Specification of Letters Patent.

Patented Aug. 7, 1906.

Application filed December 2, 1905. Serial No. 290,007.

To all whom it may concern:

Be it known that I, WILLIAM L. BIERBRAUER, a subject of the German Emperor, residing at West Hoboken, in the county of Hudson and State of New Jersey, have invented a certain new and useful Improvement 5 in Photographic-Printing Apparatus, of which the following is a specification.

My invention relates to photographic-printing apparatus commonly known as "blue-printing" apparatus; and the general object of the invention is to provide means for expeditiously forcing the backing into close contact with the glass pane.

15 In one well-known type of blue-printing frame the contact between the sensitized paper and the tracing is obtained by placing a diaphragm or imperforate blanket behind the sensitized paper and subsequently exhausting the air from between the diaphragm and the pane. The pressure of the atmosphere acting upon the back of the diaphragm thus forces it toward the pane and holds the tracing and sensitized paper in close contact 20 with each other and with the pane. In an apparatus operating upon this principle it is necessary, of course, to provide some means for preventing the leakage of air from between the diaphragm and the pane around the edges 25 of the diaphragm; and the specific object of this invention is to provide a frame or marginal rim for the diaphragm for holding down the edges thereof and advantageous means for forcing the said frame or marginal rim toward the pane.

30 Part of the object of the invention also is to provide mechanism whereby the entire side or end of the frame or a considerable part of it may be fastened down at a single operation by the movement of a single controlling member. This relieves the operator of the necessity of having to go separately to each of the several points of fastening along the edge of the frame to fasten the frame down at such 35 points.

40 My apparatus consists of two interfitting frames, and as contributory to the main object it is also an object of the invention to provide fastening means so constructed that 45 they will disappear into the outer frame when in non-active position. This permits the inner frame to be withdrawn from the outer

one without interference from said fastening means.

It is also an object of the invention to provide mechanism whereby the fastening means may be readily set and released and be secure in its position when set. 55

I attain my objects by the mechanism illustrated in the accompanying drawings, in which—

Figures 1 and 2 are back or bottom views of different frames embodying my invention.

The views are taken from the face opposite to the one exposed to the sun or other source 65 of light during the printing process. For convenience of description this will be referred to as the "back side" of the apparatus.

Fig. 1 shews a double type of frame—that is to say, one having two operating-rod on each side, each rod having its respective handle and the handles being located at opposite ends of the frame. This frame also has a separate operating-rod for each part of the frame. Fig. 2 is a single and a smaller frame 70 requiring operating-rod at the side only and each operating-rod extending the entire length of the frame, thereby necessitating but a single operating-handle. Fig. 3 is an end view of the frame looking in the direction of the arrow at A, Fig. 1, and showing the operating-handle and ratchet. Fig. 4 is a back view of a corner of the frame, showing the operating-handle and ratchet device. Fig. 5 is a sectional view taken on line 5 5, 80 Fig. 1. Fig. 6 is a view from inside the frame—as, for example, looking in the direction of the arrow at B, Fig. 1—showing the operating-rod in active position upon one of the cushion-springs of the inner frame. Fig. 90 7 is a sectional view taken on line 7 7, Fig. 1, showing the journal-bearing at the inner end of the operating-rod in the double type of device. Fig. 8 is a face view of said bearing, the view being taken in the direction of the arrow 95 C, Fig. 1. Fig. 9 is a view from the inside of the frame, showing the construction of the corner and the relative locations of the side and end operating-rod, the end rods being elevated above the side rods for non-interference with the latter. Fig. 10 is a fragmentary sectional view illustrating a possible construction of the connection between the diaphragm and the tube through which the 100

air is exhausted from beneath said diaphragm. Fig. 11 is a face view of a cushion-spring, illustrating the slotted construction at the end thereof.

5 Similar letters refer to similar parts throughout both views.

Referring first to the simpler type of apparatus shown in Fig. 2, the outer frame consists of walls *a*, having an inwardly-projecting ledge *a'* for supporting the glass pane *b*. Fitting more or less closely within said outer frame is an inner frame *c*, upon the back whereof at frequent intervals are mounted cushion-springs *c'*. By preference these 15 springs are arched flat springs, and in order to enable them to yield without buckling when pressure is exerted upon them from behind one end has a slot *c''*, as shown in Fig. 11, the other end being rigidly fastened by 20 means of a pin or screw *c'''*. A pin or screw *c''*, having a head wider than said slot, penetrates the same and enters into the back of the inner frame, which holds it. By this construction when the spring is straightened under pressure its slotted extremity slides under the head of pin or screw *c'''*; thus enabling the 25 spring to straighten without breaking or tending to loosen and pull out its fastening devices. The use of springs is not essential in 30 this apparatus; but such springs are useful in that they tend to distribute the pressure more evenly over the frame and minimize the effect of inequalities or variations of adjustment of the members which act upon them. 35 The distance from one spring to another will depend upon the stiffness of the inner frame, and in the case of a small apparatus, as shown in Fig. 2, it may be unnecessary to provide any springs at the ends of the frame, 40 the necessary pressure being transmitted from the side portions of the same.

Extending across the inner frame in position to lie adjacent to the back of the glass pane *b* is a diaphragm *d*, which may consist 45 of a rubber blanket or any fabric which is air-proof. Said diaphragm makes air-tight contact with said inner frame, or at least is secured therein in such manner as to make air-tight connection therewith when the inner 50 frame is forced down upon the back of the glass pane *b*.

The pressure members, which are adapted to act upon the back of the springs *c'* to force the inner frame toward the pane, consist in 55 the present design of fingers or levers *e'*, which are rigidly secured to the operating-rod *e*, rotatably mounted upon the outer frame *a*. These fingers are so arranged as to come opposite to the spring *c'* approximately 60 at the middle thereof, so as to force the same downward when rods *e* are rotated in the proper direction, this action being illustrated, for example, in Figs. 5, 7, and 9. In order that said fingers and their operating-rods 65 may not interfere with the inner frame *c*

when it is being lifted out of the outer frame, said outer frame is recessed or rabbeted longitudinally on the inside and said rods are mounted within them, as best shown in Figs. 5 and 9. Besides the recess or rabbet *a⁶* for the rods *e* are the vertically-extending recesses or rabbets *a²* for receiving said fingers *e'* when the latter are rotated to raised position, as indicated in dotted lines, Figs. 5 and 9.

Rods *e* are journaled, preferably, in end plates *a³* *a⁴*, which for convenience may be located on the outside surfaces of the outer frame at the ends thereof. At the end of rods *e* outside of the frame is rigidly secured an operating-handle *f*. (Shown in detail in 75 Figs. 3 and 4.) A pawl or dog *f'* is pivoted to each of said handles in position to engage the teeth of a ratchet plate or quadrant *a⁵*, rigidly secured to the end plate *a⁴*. A spring-influenced latch or finger-piece *f²* is mounted upon said handle *f* and connected to pawl *f'* to release the same in the well-known manner. This ratchet device is so arranged that when the handles and rods *e* are rotated in direction to lower the fingers *e'* upon springs 90 *c'* the teeth of the ratchet will automatically engage pawl *f'* and retain the parts in set position; but when pressure is exerted upon the latch *f²* the pawl *f'* will be released from the ratchet-teeth and permit the fingers to be 95 rotated to raised position, as shown in Figs. 5 and 9.

Suitable means for exhausting the air from beneath the diaphragm are indicated in Fig. 10. The diaphragm *d* is apertured at one or 100 more points, and at such points an eyelet *g* is secured, each eyelet having an upwardly-extending neck *g'*, over which may be slipped a rubber tube *h*. Said tube will be connected to the receiver of an exhaust-pump. The 105 pump is not shown, as it forms no part of the present invention.

The double or multiplex type of apparatus illustrated in Fig. 1 is the same as that shown in Fig. 2 and hereinabove described, 110 except that there are two operating-rods *e* on each side of the frame and there is an operating-rod at each end of the frame. This type is designed for use where the frame is so long that a single operating-rod would not have 115 sufficient resistance to torsional strain to hold all of its fingers down tight enough upon the inner frame. In this multiplex type it is necessary to provide a journal-bearing for the inner ends of the operating-rods where 120 they come together, and such a bearing is illustrated in Fig. 8. It consists merely of two plates or journals *i i*, secured in proper position in the outer frame.

When end rods are employed in addition 125 to the side rods, as shown in Fig. 1, it is necessary to offset them so that one will not interfere with the other where they cross at the corners of the frame. These relative positions are illustrated in Figs. 5, 7, and 9. 130

With this construction the fingers *e'* on the higher of the two rods are longer than the fingers on the lower one in order that they may reach down to the springs *c'*.

- 5 In operation the outer frame supporting the glass pane is turned to reverse position with its back lying upward, as shown in Figs. 1 and 2. After the tracing, with the sensitized paper on top of it, has been laid upon the pane, the diaphragm or blanket *d* is superimposed and the inner frame *c* is lowered into position in the outer frame. The handles *f* are then rotated to such position as to lower the fingers *e'* upon the equalizing or cushion springs *c'*. Sufficient pressure is exerted upon the handles to bring the inner frame and diaphragm down close upon the pane to thereby make air-tight contact at the periphery of the diaphragm. The air is then exhausted through the tube *h*, and the atmospheric pressure acting upon the back or outer surface of the diaphragm holds the tracing and sensitized sheet in close contact with each other and with the glass pane *b*.
- 20 25 The frame is then turned over and its face exposed to the sun or electric light for printing, after which the frame is turned back again to the original position. The operating-handles *f'* are then released, and the inner frame is lifted out, thus affording access to the sensitized paper.

What I claim as new, and desire to secure by Letters Patent, is—

1. Photographic-printing apparatus comprising a glass pane, an open frame adapted to support the same, an air-tight diaphragm designed to lie back of the glass pane, an inner frame adapted to lie back of said diaphragm, pressure members mounted in said outer frame in position to press upon said inner frame to force the same against said diaphragm, and means for operating a plurality of said pressure members in unison.

2. Blue-printing apparatus comprising a glass pane, a frame having ledges thereon against which the edges of the glass may lie, a backing adapted to lie back of the glass, an operating-rod running along the frame near the edge of the backing, and a plurality of fingers rigidly set on said rod for forcing said backing toward the glass.

3. Blue-printing apparatus comprising a glass pane, an outer frame having ledges thereon against which the edges of the glass may lie, a backing adapted to lie back of the glass, a rod running along the frame near the edge of the backing, a handle for operating said rod, and a plurality of fingers for acting upon said backing, said fingers being secured to said rod, whereby all of them are operated from said handle.

4. Blue-printing apparatus comprising a glass pane, an outer frame having ledges thereon against which the edges of the glass may lie, a backing adapted to lie back of the

glass, a rod running along the frame near the edge of the backing, a plurality of fingers operative upon said backing and rigidly set on said rod, a handle for rotating said rod for operating said fingers, and a ratchet device for retaining said rod in selected position.

5. Blue-printing apparatus comprising a glass pane, a frame having ledges thereon against which the edges of the glass may lie, an inner frame adapted to lie back of the glass, a rod running parallel with the edge of the frame and extending to the end thereof, a plurality of fingers mounted on said rod for acting upon said inner frame and a handle secured to said rod outside of the outer frame at the end thereof for operating said rod.

6. Blue-printing apparatus comprising a glass pane, an outer frame having ledges thereon against which the edges of the glass may lie, a backing consisting of an inner frame fitting into said outer frame and having a blanket extending across it and making air-tight connection therewith, a rod running along the outer frame, a plurality of fingers operative upon said inner frame and rigidly set upon said rod for forcing said inner frame toward the glass, a handle for rotating said rod, and means for setting said rod in desired position.

7. In a blue-printing apparatus the combination of a glass pane, an outer frame adapted to support said pane, an inner frame adapted to lie back of said pane, a diaphragm extending across said inner frame, a rod rotatably mounted in one of said frames, a plurality of fingers secured to said rod and adapted to engage the other of said frames for forcing the inner frame toward said pane; and means for operating said rod.

8. In a blue-printing apparatus the combination of a glass pane, an outer frame adapted to support said pane, an inner frame adapted to lie back of said pane, a diaphragm extending across said inner frame, a rod rotatably mounted in one of said frames, a plurality of fingers secured to said rod and adapted to engage the other of said frames for forcing the inner frame toward said pane; a handle for rotating said rod and a ratchet device for releasably retaining said rod in set position.

9. In a blue-printing apparatus the combination of a glass pane, an outer frame adapted to support said pane, an inner frame adapted to lie back of said pane within said outer frame, a diaphragm secured to and extending across said inner frame, a rod rotatably mounted across said outer frame, a plurality of members fastened to said rod for engaging said inner frame to force it toward the pane, a handle for rotating said rod and a ratchet device for releasably retaining said rod in set position.

10. In blue-printing apparatus the combination of a glass pane, an outer frame adapt-

ed to support said pane, an inner frame adapted to lie back of said pane within said outer frame, a diaphragm secured to and extending across said inner frame, springs on the back of said inner frame, a rod rotatably mounted in said outer frame, a plurality of members fastened to said rod and adapted to abut said springs for forcing them and the inner frame toward the pane, and means for operating said rod.

11. Blue-printing apparatus comprising two interfitting frames, the inside frame having a diaphragm and the outside frame having a ledge acting as a stop against which the inside frame may lie; a rod running lengthwise of the outside frame, and rotatable

about its own axis; and a plurality of fingers secured to said rod for acting upon the inside frame to force it toward the ledge on the outside frame, said rod being let into said frame for non-interference with the inner frame when the latter is being withdrawn from the outer frame, and said outer frame being chambered for receiving said fingers when rotated to inactive position.

25

In witness whereof I have hereunto subscribed my name in the presence of two witnesses.
